UNITED STATES PATENT OFFICE.

PAUL A. WAGNER, OF CARLSTADT, NEW JERSEY.

HEDDLE FOR LOOM-HARNESS.

1,112,740.

Specification of Letters Patent.

Patented Oct. 6, 1914.

Application filed June 12, 1911, Serial No. 632,700. Renewed March 4, 1914. Serial No. 822,478.

To all whom it may concern:

Be it known that I, PAUL A. WAGNER, a citizen of the United States, residing at Carlstadt, in the county of Bergen and State 5 of New Jersey, have invented a certain new and useful Improvement in Heddles for Loom-Harness, of which the following is a specification.

The invention relates to the heddle-eye 10 or mail and means for engaging the latter with the heddle, and the object of the invention is to provide a mail of metal which may be easily and economically manufactured and secured to the loops or legs of the heddles, and in which projecting points or angles are avoided, and which shall be flat 15 and thin, occupy but little space, and tend to lie in the same plane with the heddle-loops.

The invention consists in certain novel 20 features and details of construction and arrangement by which the above objects are attained, to be hereinafter described and pointed out in the claims.

The accompanying drawings form a part 25 of this specification and show preferred forms of the invention.

Figure 1 is a face view of a mail formed by flattening a complete annulus of metal, the eye being produced by punching out a 30 portion of the metal of the body. Fig. 2 is an edge view of the same. Fig. 3 is a corresponding longitudinal central section. Fig. 4 is a transverse section taken on the line 4—4 in Fig. 1. Fig. 5 shows a face view 35 of a mail formed as in Fig. 1 by flattening a complete annulus but with the warp-eye produced by bending the body members from each other. Fig. 6 is an edge view of the same. Fig. 7 is a corresponding longitudinal central section. Fig. 8 is a transverse section taken on the line 8—8 in Fig. 40 5. Fig. 9 is a face view of a mail similar to that shown in Fig. 1 but formed by folding a strip of metal instead of by flattening an annulus. Fig. 10 is a corresponding longitudinal central section.

The size is for clearness of illustration greatly enlarged in all the forms shown.

Similar letters of reference indicate like 45 parts in all the figures.

Referring to Figs. 1 to 4 inclusive, the mail comprises an endless ring or annulus, such as results from shearing off a short length from a thin tube, flattened to produce

a body portion formed by the two members 55 A, B, connected at the ends by the bights C, D, in which the loops forming the legs F, G, of the heddle are received and held by pinching the metal strongly thereupon. The mail thus formed is preferably tapered 60 slightly toward the bights C, D, and a warp-eye H is produced by punching an elongated perforation through both members A and B, as shown. The mail previous to its attachment to the heddle threads is agitated for a 65 suitable period with its fellows in a tumbling-barrel or analogous device to remove the sharp angles and any roughnesses and when subsequently attached to the legs F, G, and pinched thereon, presents no angles 70 or projections likely to interfere with its movements relatively to the adjacent mails and heddles.

In the form shown in Figs. 5 to 8 inclusive, the annulus is of the same width 75 throughout, and the members A¹ B¹ are separated or bent laterally from each other, but in the direction of the plane of the surfaces, to form an eye H¹. The legs F¹ G¹ are held in the bights C¹ D¹ as before. In this form 80 it is preferable to pass the warp-thread outside the member A¹, through the eye H¹ and outside the member B¹, as shown in Figs. 5 and 8, to lessen the danger of the thread 85 engaging in the angle at each end of the eye.

Figs. 9 and 10 show a form similar to that first described but formed by bending a strip instead of using the complete annulus. It comprises a single member A² having its ends B² pointed and folded upon the member A² to produce bights C² D² in which the legs F² G² of the heddle are held as before. The eye H² is punched as in the first-described form. Perforations a a are provided in which the pointed ends B² are sunk, and 90 the body portion of the member A² is slightly bent or offset at a¹ a¹ to aid further in preventing interference between the pointed ends of adjacent mails.

It will be noted that in all the forms the 100 plane of the mail coincides with the planes of the heddle loops so that when the harness is engaged with the laths, not shown, the mails will receive the warp-threads with but little twisting or distortion of the legs, and 105 consequently may stand very closely together with a corresponding saving of space.

The metal used is extremely thin; the en-

tire thickness of the completed mail is but little if any greater than that of the thread composing the heddle.

I claim:—

- 5 1. In a heddle, a mail comprising a metal body folded upon itself to form at each end a transverse bight with an integral intermediate body portion having an opening for the reception of a warp-thread, and a 10 heddle-loop received in and held by each of said bights with a portion thereof lying transversely of the length of said body, said body, opening and loops lying in the same plane.
- 15 2. In a headle, a mail comprising an annulus flattened upon itself to produce a body-portion and a bight at each end thereof, said body having an opening for the reception of a warp-thread, and a heddle-loop received in and held by each of said bights.
- 20 3. A mail comprising an annulus flattened

upon itself to provide a body-portion, and a bight at each end thereof, said body having an opening therein for the reception of a warp-thread, and said bights adapted to 25 receive and hold heddle-loops.

4. A mail comprising an annulus flattened upon itself to provide a body-portion of two parallel adjacent members and a bight at each end thereof joining said members, said 30 body having a warp-eye therein formed by perforating both said members, and said bights adapted to receive and hold heddle-loops.

In testimony that I claim the invention 35 above set forth I affix my signature, in presence of two witnesses.

PAUL A. WAGNER.
